UNITED STATES PATENT OFFICE.

ROBERT BOLLINGER, OF FREELAND, MARYLAND.

EXTENSION-BED.

No. 819,631.

Specification of Letters Patent.

Patented May 1, 1906.

Application filed May 3, 1905. Serial No. 258,644.

To all whom it may concern:

Be it known that I, ROBERT BOLLINGER, a citizen of the United States, residing at Free-
land, in the county of Baltimore, State of
Maryland, have invented certain new and
useful Improvements in Extension-Beds;
and I do hereby declare the following to be a
full, clear, and exact description of the inven-
tion, such as will enable others skilled in the
art to which it appertains to make and use
the same.

This invention relates to bedsteads, and
more particularly to the extension variety of
bedsteads.

One object of the invention is to provide a
bedstead of such character that it may be
readily changed from a double to a single
bedstead.

Another object of the invention resides in
the provision of a bedstead wherein the head
and foot boards will be so constructed and ar-
ranged that each may receive an intermedi-
ate member for converting the bedstead from
a single to a double one and wherein the slats
of the bedstead will be so constructed as to
accommodate either a single or double bed-
stead.

A still further object of the invention re-
sides in the provision of a comparatively sim-
ple, inexpensive, durable, and efficient bed-
stead of the adjustable character hereinafter
set forth.

With these and other objects in view the
present invention consists in the combination
and arrangement of parts, as will be herein-
after more fully described, shown in the ac-
companying drawings, and particularly pointed
out in the appended claims, it being un-
derstood that changes in the form, propor-
tion, size, and minor details may be made
within the scope of the claims without depart-
ing from the spirit or sacrificing any of the
advantages of the present invention.

In the accompanying drawings, Figure 1 is
a perspective view showing the removable
portions in position and illustrating the side
portions separated therefrom, the connect-
ing-strips being broken to permit of such sepa-
ration. Fig. 2 is a rear elevation of the head-
section in position as a single bed. Fig. 3 is
a rear elevation of the removable head sec-
tion. Fig. 4 is a perspective of a portion of
one of the side pieces, showing the arrange-
ment of the slats. Fig. 5 is a perspective
view of a portion of one of the posts and its
plate, the plate being removed from the post

to show the openings. Fig. 6 is a perspective view of an end of one of the side rails.

Referring now to the accompanying draw-
ings, and more particularly to the construc- 60
tion embodying a single bedstead, it will be
seen that the reference characters 1 and 2
designate sections forming the head of the
bedstead and the characters 3 and 4 indicate
sections of the footboard of the bedstead, the 65
sections of the headboard being of a width
corresponding to the alining footboard.

The headboard-sections are provided with
posts 6 and 7 along their outer longitudinal
edges, upon the inner face of each of which is
a pair of upper and lower sockets 8 and 9, and
over each of these pair of sockets is arranged
a plate 12, in each of which is formed a pair
of alining keyhole-slots 13 and 14, which reg-
ister, respectively, with the upper and lower 70
openings 8 and 9 of the head-posts, the plates
being secured to the said posts by means of
suitable screws 15 or other fastenings, as well
understood.

The posts 16 and 17 of the footboard-sec- 80
tions are each provided with upper and lower
recesses similar to those described in connec-
tion with the posts of the headboard and
over which are fitted plates 12, which are also
provided with the upper and lower keyhole- 85
slots 13 and 14. These plates of the head
and foot boards with their keyhole-slots reg-
ister with respect to the slots of a head-sec-
tion and a foot-section for the reception of
the upper and lower heads 22 and 23 in the 90
ends of the side rails 24 in a manner well un-
derstood. It is obvious, however, that but
one keyhole-slot in the head and foot boards
and a single-headed member in the ends of
the corresponding rails may be employed for 95
the purpose of supporting the side rails with
respect to the head and foot board sections.
Each side rail is provided upon its inner face
with the usual notched cleat 25, the notches
26 of each rail being in alinement with the 100
notches upon the inner face of the opposite
rail for the reception of the slats 27, to be
hereinafter more fully described.

Secured throughout the back of each of the
head-posts 6 and 7 is a strip of wood or other 105
suitable material 28 and 29, respectively,
while secured along the longitudinal inner
edge of each head-section is another strip 30
and 31. It will thus be understood that
there are four cleats or strips projecting from
the rear of the head-section and reference to
the drawings will disclose that each of these

four strips has a series of openings 32 through their side faces, the openings or slots 32 of each rear strip or cleat alining in series, one series above another for the reception of horizontal strips 33, 34, and 35, the ends of the strips 33 and 35 being fixedly secured in the openings or slots 32 of the rear longitudinal cleat or strip 28, with their opposite ends enlarged, as at 33' and 35', for tight fit in the corresponding openings or slots 32 of the rear cleat or strip 29, the horizontal strip 34 being fixedly secured in the intermediate slot or opening in the head-post 29 and passed through the remaining alining slots in the strips 30 and 31 and enlarged, as at 34', for tight detachable fit in the corresponding intermediate slot of the rear cleat or slot 38. When the head-sections 1 and 2 have their inner longitudinal edges in engagement with each other, these strips 33, 34, and 35 are fitted in the alining openings in the said strips 28, 29, 30, and 31 with their ends lying flush with the outer edges or faces of the head-posts 6 and 7. In practice the outer faces of these longitudinal strips 28, 29, 30, and 31 and the horizontal strips 33, 34, and 35 would be hidden from view by reason of a panel work or boarding, (not shown in the drawings,) but which would be employed in practice for the purpose of protecting and hiding the parts arranged therebetween and the back of the panel-work of the headboards 1 and 2.

The posts 16 and 17 of the footboards also have longitudinal cleats 36, 37, 38, and 39, respectively, which are provided with openings or slots 40 for the reception of three horizontally-arranged strips 41, 42, and 43, designed for sliding engagement in the slots and whereby the footboards may be supported in a manner similar to that described in connection with the headboard. It may be stated that the horizontal strip 42 is fixedly secured to the foot-post 36 and has its opposite end 42' enlarged for engagement in the corresponding slot in the foot-post 37, the corresponding ends of the horizontal members or strips 41 and 43 being fixedly secured in the corresponding slots of the footboard 37 and passed through alining slots in the remaining vertical or longitudinal strips with their free ends 41' and 43' enlarged for tight detachable fit in the corresponding fit-slots of the foot-post 36. It might be stated at this time that the enlargements at the free ends of certain of the horizontal strips of the head and foot board sections are enlarged not only for the purpose of tight fit within the corresponding slots of the posts, but also to limit the outward movement of the head and foot board sections when they are separated for the purpose of inserting the intermediate head or foot section for the purpose of converting the bedstead from a single to a double one. It might be stated also at this time that the

horizontal strips or members will be hidden from view by a panel work or boarding, causing the sliding strips or members 41, 42, and 43 to be confined therebetween and the rear faces of the panel-work of the footboard-sections. 70

From the foregoing the construction of a single bedstead in accordance with my invention will be understood, and in order that the extensible feature of my invention will be 75 readily comprehended reference to Fig. 1 of the drawings will disclose that the headboard-section 44 is constructed with its forward face of the same character as that employed for the head-section hereinbefore described, 80 the rear face 45 of the detachable head-section having longitudinal strips 46 and 47 along its edges upon each of which is disposed an upper and lower plate 48 and 49 and 48' and 49', respectively. Each of these plates 85 is secured to the corresponding longitudinal strip 46 and 47 by means of rivets or the like 50 and are bent outwardly intermediate their ends, as at 51, and then downwardly, as at 52, the parts 52 of each plate lying parallel 90 with the corresponding face of the corresponding strips 46 and 47. Now when it is desired to convert the bedstead from a single to a double one these hooked plates are engaged with the horizontal strips 33 and 35 of 95 the headboard-sections. In other words, the rear faces of the strips 46 and 47 of the detachable head-section 44 have their upper and lower hook-plates arranged to engage over the corresponding upper and lower horizontal strips 33 and 35, the portions 51 of the hook-plates lying upon the upper edge of the corresponding horizontal strip with their downwardly-bent portions 52 lying flush with the outer faces of the said strips. It will be 100 observed that these hook-plates do not engage the intermediate horizontal strip 34, the plates for engaging this particular strip being entirely unnecessary. The footboard is provided with a detachable foot-section 53, having its back constructed and arranged the same as the back of the detachable head-board-section, so that it may be engaged with the corresponding upper and lower horizontal strips 41 and 43 of the footboard. It 110 will thus be understood that when the head and foot sections of a single bedstead are supported in the manner described these detachable head and foot board sections may be inserted intermediate the end sections, 115 converting the bedstead from a single to a double one. It will be understood, too, that these intermediate detachable head and foot board sections may be readily detached from the head and foot board sections and the corresponding horizontal strips of the head and foot boards, together with the sections to which they are secured, may be forced inwardly toward each other with respect to the sections of the head and foot boards to fill up 120 125 130 135

the spaces caused by the withdrawal of the intermediate sections, as should now be well understood.

5 The head-sections, including the intermediate detachable one, are provided with upper strips 53' for the purpose of ornamentation, and the tops of the footboards are provided with similar strips 54 for a like purpose. Of course this is but one feature of ornamentation, and the head and foot boards may 10 have their exterior surfaces ornamented in any suitable manner—such, for instance, as panel-work or the like.

15 Since the rails carried by the respective end sections of the head and foot boards are adjustable toward and away from each other, it is obvious that slats should be used with my improved bedstead of such character that they may be adjusted according to the adjustment of the head-sections and rails 24 toward and away from each other. Therefore 20 it will be seen that I construct the slats so that they may be adjustable, each slat consisting of two members 55 and 56, arranged 25 one upon the other, the inner end of each strip 55 and 56 having a loop 57 and 58, respectively, engaging the opposite strip 55 and 56, whereby the strips 55 and 56 may be in telescopic association with each other, so 30 that their free ends may be engaged in the corresponding notches 26 of the rails 24 in the manner which should now be well understood.

What is claimed is—

1. A bedstead comprising head and foot 35 boards including end and intermediate sections, rails connecting the end sections of the head and foot boards, opposing horizontal strips carried by the end sections of the head and foot boards, hooked attaching members 40 carried by the intermediate sections of the head and foot boards for engagement with the said horizontal strips, and means carried by said strip for limiting the separation of the said end sections. 45

2. A bedstead comprising head and foot boards including end and intermediate sections, rails connected to the end sections of the head and foot boards, opposing horizontal strips carried by the end sections of the 50 head and foot boards, hooked attaching-plates carried by the intermediate sections of the head and foot boards for engagement with said horizontal strips, side posts associated with said end sections, said side posts 55 having openings therein for the passage of said strips, and shoulders formed on said strips to engage the said side posts to limit the separation of the said end sections.

In testimony whereof I affix my signature 60 in presence of two witnesses.

ROBERT BOLLINGER.
